UNITED STATES PATENT OFFICE.

GEORGE A. ARNOLD, OF BROOKLYN, NEW YORK, ASSIGNOR OF ONE-HALF TO JOHN C. W. BEALL, OF WASHINGTON, DISTRICT OF COLUMBIA.

CIGAR-CUTTER.

No. 903,431.

Specification of Letters Patent.

Patented Nov. 10, 1908.

Application filed June 20, 1908. Serial No. 439,585.

To all whom it may concern:

Be it known that I, GEORGE A. ARNOLD, a citizen of the United States, residing in Brooklyn, county of Kings, State of New York, have invented certain new and useful Improvements in Cigar-Cutters; and I do hereby declare the following to be a full, clear, and exact description of the invention, such as will enable others skilled in the art 10 to which it appertains to make and use the same.

The object of the invention is to provide a simple and efficient form of cigar cutter particularly adapted for use in connection 15 with a pencil or other writing instrument and a rubber eraser, and to this end comprises an outer tubular member having lateral opposed openings, an inner tubular slide- 20 able member in the outer member and like- wise having lateral opposed openings, one of 25 which is provided with a cutting edge, the outer tubular member having a shoulder below the lower end of the inner member, which latter is turned inwardly to form a flanged shoulder, with a helical spring 30 interposed between said shoulders which serves to move the inner tubular member relatively to the outer member to cause the openings in the two members to register, and a pin 35 and slot connection between the inner and outer tubular members to limit the relative movements of the respective members in both directions. As a matter of utility, convenience and economy, the outer tubular member is adapted to receive and hold in its 40 lower end, a pencil or like writing instrument, and in its upper end, a rubber eraser is removably secured, the resulting combination instrument being exceedingly simple in 45 construction, involving as it does relatively few parts, efficient in operation, and readily and cheaply manufactured as compared with implements of this character as heretofore known.

50 In the accompanying drawings, Figure 1 is a vertical elevation of the improved cigar cutter with the eraser and pencil applied thereto. Fig. 2 is a vertical section through the same. Fig. 3 is a similar section taken 55 at right angles to that indicated in Fig. 2.

Referring to the drawings, *a* indicates the main member of the cutter, which consists of a relatively thin metal tube, provided at a point above its lower end with a groove *b*, 55 which forms a peripheral shoulder on the

interior of the tube, and the lower end of said tube is provided with a longitudinal slot *s*, by reason of which said lower end constitutes a clamp to hold a pencil *x* or similar writing instrument. Near its upper 60 end, said tubular member *a* is provided with openings *c* and *d* in its sides which are disposed opposite each other, the opening *c* being of sufficient size to receive the tip of a cigar and the opening *d* preferably being 65 made somewhat larger to freely discharge the severed tip. Preferably the lower rim of the opening *c* is provided with a cutting knife edge.

Telescopically mounted within the upper 70 end of the tubular member *a* and fitted within the same for easy sliding movement is an inner tubular member *e*, which is likewise provided with opposed lateral openings *f* and *g* of substantially the same size as the 75 corresponding openings *c* and *d* in the outer member *a*. The upper rim portion of the opening *f* is provided with a knife edge which coöperates with the corresponding knife edge on the lower rim of opening *c* 80 when said inner tube is forced downwardly in the outer tube. The lower end of the inner tube is turned inwardly to form a flanged shoulder *h* and between said shoulder and the annular shoulder *b* on the outer 85 tube, there is interposed a helical spring *i* which serves to move the inner tube outwardly with respect to the outer tube and to bring the openings in the respective tubes 90 into registry.

In order to limit the relative movements of the inner and outer tubes, said tubes are conveniently connected by a pin and slot engagement, a convenient form of which is illustrated, and consists of a pin *k* passed 95 through and secured in opposite sides of the outer tube, and engaging opposite slots *j* in the inner tube, which latter slots are made sufficiently long to permit the inner tube to be moved a proper distance in the outer 100 tube to cause the knife edge on the rim of opening *f* to pass over the coöperating knife edge on the rim of opening *e*, and sever the tip of a cigar which is inserted in the registering openings *c* and *f*, when the inner tube is in its upper position. In the outer 105 end of the inner tube is removably secured a piece of rubber or the like to serve as an eraser.

When it is desired to clip the end from a 110

cigar, the tip of the latter is inserted in the registering openings *c* and *f* and the inner tubular member is forced down against the tension of spring *i* until the knife edge on 5 the upper portion of the rim of opening *f* passes through and severs the tip of the cigar, the severed tip being ejected through the openings *d* and *g* when the inner member is returned to its normal position by the 10 spring *i* after the pressure on the inner end of said tubular member has been released.

What I claim is:—

A cigar cutter, comprising an outer tubular member having opposed lateral openings, 15 an inner tubular member slidable in the outer member and having lateral opposed

openings, one of which is provided with a cutting edge, the outer member having a shoulder below the lower end of the inner member and the latter having a flanged shoulder at its lower end, a spring interposed between said shoulders, and a pin and slot connection between the inner and outer members to limit the telescoping movement of said members. 25

In testimony whereof I affix my signature, in presence of two witnesses.

GEORGE A. ARNOLD.
